UNITED STATES PATENT OFFICE.

WILLIAM P. LOCKE, OF CHICAGO, ILLINOIS, ASSIGNOR TO WALLACE G. CLARK, OF CHICAGO, ILLINOIS.

CHAIN SYSTEM OF LOCK CONTROL.

1,134,625.

Specification of Letters Patent. Patented Apr. 6, 1915.

Application filed October 9, 1913. Serial No. 794,222.

To all whom it may concern:

Be it known that I, WILLIAM P. LOCKE, a citizen of the United States, residing at Chicago, county of Cook, State of Illinois, have made a certain new and useful Invention in Chain Systems of Lock Control, of which the following is a specification.

This invention relates to a chain system of lock control.

10 The object of the invention is to provide greater security in locking and controlling devices for the doors, windows, or other closures of stores, safes, offices, factories, dwellings or the like.

15 A further object is to provide means which are simple and efficient whereby the doors, windows or other closures or a series or chain of such devices can not be locked or unlocked unless and until a preceding 20 closure of the series is locked or unlocked as the case may be.

A further object is to provide simple and efficient means whereby a series or chain of closures, such as doors, windows, or the like are individually or independently locked or unlocked, and wherein the locking of one closure of the series serves to release a key necessary to effect the locking of the next consecutive closure of the series.

30 A further object is to provide a key releasing lock system of the nature referred to wherein the unlocking of any closure of the system or chains is a necessary precedent of the unlocking of the next consecutive closure of the series or system.

A further object is to combine with the key releasing lock system of the nature referred to and including a series or chain of independent secondary locks, a master or 40 primary lock of the recording type wherein the identity of the key employed to lock or unlock the same together with the time of its operation may be recorded, and the unlocking of which is necessary to be accomplished in order to release the key required to unlock the next succeeding secondary lock.

A further object is to provide a system of 50 the nature referred to wherein the master or recording lock can not be locked until the preceding secondary lock of the system has also been properly locked.

A further object is to provide key releasing mechanism which is simple and efficient.

Other objects of the invention will appear more fully hereinafter.

The invention consists substantially in the construction, combination, location, relation, relative arrangement of parts and system, all as will hereinafter be more fully set forth, as shown in the accompanying drawings, and finally pointed out in the appended claims.

In the drawings:—Figure 1 shows a series of locks as embraced within a chain or succession of interrelated locking devices. Fig. 2 is a detail view in section of a key barrel showing the application thereto of a key for operating a lock bolt. Fig. 3 is a view in section on the line 3, 3 Fig. 4, looking in the direction of the arrows, showing a secondary lock and key release device employed in connection with my invention. Fig. 4 is a view in elevation of a secondary lock and key release device, the front plate 75 of the casing removed. Fig. 5 is a view in elevation showing a door and the application thereto of a secondary lock and key release device embodying my invention.

The same part is designated by the same reference numeral wherever it occurs throughout the several views.

In accordance with my invention I propose to employ a series of locks which may be of any suitable or desired construction but each requiring two keys for its operation and a key section for each key. One of the two keys for each lock I will call the bolt operating key and the other the releasing key. The keys may be of any suitable type, such, for instance, as the ordinary Yale key, and the key sections are made to correspond to the keys employed. I so construct the key sections that the releasing key of one lock is the bolt operating key of the immediately preceding lock of the system or series of locks, or, it may be, of the immediately succeeding lock of the series or system. I also so construct each lock mechanism that the releasing key thereof cannot be detached therefrom until the bolt operating key of that lock has been inserted in its key section and operated, and the bolt operating key can not be detached until the releasing key has been inserted in its key section and operated. With this arrangement and relation, it will be readily seen that each lock of the entire system or series must be

operated in order to properly operate one of them. It will also be seen that as many such locks as desired may be employed in any system or chain.

5 In practice I prefer to use a lock mechanism of the key indicating or recording type as the primary or master lock while the remaining locks of the system or series may be called secondary locks. In case the primary or master lock is of the recording type 10 it is evident that any of the commercial forms of recording locks may be used. In practice I prefer to use as the master lock a lock of the recording type in which a plurality of bolt operating or controlling keys are employed which respectively differentiate from each other in some particular, the recording mechanism operating to record the identity of each particular key when 15 used and the date and time of its use. In this case a differentiated key must be used in the lock to release an auxiliary key, and the key so released then becomes the releasing key for the bolt controlling key of the 20 next lock of the series or system, and so on through as many secondary locks as may be 25 included in the system, the last released key of the system being retained by the user.

In the use of this system let it be supposed that all of the secondary devices of 30 the entire system are properly locked and the master or recording device is also locked properly. In this condition the auxiliary key of the master lock will be in its key section of that lock and incapable of removal until the bolt controlling key of the master or recording lock has been inserted in its proper section and operated to withdraw the bolt of the said recording lock, in which case 35 the identity and time of operation of said key will be recorded. Under the supposition above made each secondary lock of the entire series or chain will have its bolt operating key inserted in its proper key section with 40 the bolt thereof shot or extended but said bolt operating key cannot be withdrawn nor manipulated to withdraw the bolt which it operates or controls. When the auxiliary key of the master or recording lock has been 45 withdrawn from said lock, after being released by the action of the differentiated key, as above described, then said auxiliary key is employed to release the bolt operating key of the first secondary lock of the 50 series, and permit said key to withdraw the bolt of its lock and then to be withdrawn from the lock. This key then becomes the releasing key of the next secondary lock of the series and so on. In order to again operate 55 the bolt of the master lock, that is, in order to shoot said bolt into locking relation, it is first necessary to insert the released key of the last secondary lock of the series or system into its bolt operating key 60 section, and shoot the bolt of that lock,

which action not only operates said bolt to locking position but it permits the releasing key of said lock to be released and withdrawn, the bolt operating key of said lock now remaining in its key section being held 70 therein against operation or withdrawal. The key thus released then is used as the bolt operating key for the next preceding lock of the system and so on throughout the entire chain of locks until the master lock 75 is reached, the key released from the first secondary lock of the system now being used as the auxiliary key for the master lock. It is obvious that the unlocking operation may terminate at any desired secondary lock, in which case the remaining locks of 80 the system will remain undisturbed. In this case the locking operation must commence with the secondary lock where the unlocking operation ceased.

In Fig. 1 I have indicated a master or recording lock at A, having the differentiated key section 6, and the auxiliary key section 7. At B, C, D, I have indicated secondary locks each having a bolt operating key section 9, and a key releasing key section 10. The auxiliary key 8 when released from lock A is inserted in key section of lock B, and operated to release the key 11, which operates in the bolt operating key section 9 of lock B. The key 11 then is inserted in the key section 10 of the lock C, to release key 12 from key section 9 of lock C, the key 12 then is employed in key section 10 of lock D to release key 14 from key section 9 of lock D and so on. The secondary locks and the bolt operating and key releasing devices thereof may be of any suitable construction. A simple arrangement is shown wherein each lock comprises a casing 15, in which the bolt 16 is mounted to slide. The shank of the bolt is engaged in any convenient way by the bolt operating key section 9, thereof, whereby, when the bolt operating key is turned the bolt is moved. A simple embodiment of this idea is shown wherein the section 9 is provided with a segment gear 17 arranged to mesh with rack teeth 18, formed in the shank of the bolt. In order to permit the bolt operating key to 110 be withdrawn from the section 9, the bolt must be withdrawn from its projected or locking position. The releasing key section 10, carries a cam member 19, at its end, and the shank of the bolt 16, is formed with a 115 shoulder 20, behind which the cam 19, engages when the bolt is in projected position and the key section 10 is turned. This section cannot be turned until the bolt is in projected position for the reason that the 120 cam 19 will strike against the edge of the bolt shank and will be held against turning until the shoulder 20 has passed the path of operation of the cam, and this must occur before the releasing key can be withdrawn 125

from the key section 10. The key sections 9, 10, may be supported in the casing 15 in any suitable or convenient manner. For 5 illustrating purposes I have shown brackets 21, for this purpose. In like manner the bolt 16 may be held and guided in any suitable or convenient manner.

It may be sometimes desired to insure that the door, window or other closure to which 10 a secondary lock is applied is fully closed and locked when the bolt operating key thereof is operated, thus guarding against the danger of the bolt being shot before it is in position to engage its keeper. A simple arrangement for accomplishing this purpose is shown wherein a closure locking rod 15 22 is employed and associated with the secondary lock. The rod is arranged to pass through the lock casing and alongside the bolt 16, and its end 23 is designed to enter a socket or seat in the closure framing only when the closure is in fully closed position. The locking rod is provided in the side 20 thereof with a transverse notch 24, which, when the end of said rod is seated in its 25 socket in the closure framing, is brought into line with a rib 25 formed on the shank of the bolt, thereby permitting the bolt to be projected into locking position only when 30 the rod is in locking position also. When the rod is withdrawn from locking position the notch is carried out of register with the rib 25 and consequently the bolt can not be projected. The locking rod 22 may be 35 held from turning in any convenient manner. A simple arrangement is shown wherein a transverse pin 26 is carried by said rod the ends of which bear against the guiding 40 surfaces 27 of the casing and prevent axial movement of said rod.

A locking system as above described may be applied in any situation where locks may be desired such as the doors, windows, gates, shutters or other parts of dwellings, business houses, offices, factories, shops, stores, cars, safes, and in fact wherever locks may be required.

Having now set forth the objects and nature of my invention, and a construction, 50 arrangement, and system embodying the principles thereof, what I claim as new and useful, and of my own invention, and desire to secure by Letters Patent, is—

1. A locking system including a plurality 55 of lock devices, each employing an operating and a release key, the operating key of one constituting the release key of the next succeeding one of the series, one of said keys being always retained in each of said devices, and means whereby when one of said 60 keys is in operating position the other is released for removal.

2. A locking system including a master lock and series of secondary locks, operat-

ing keys for the master lock, an auxiliary key for the master lock, said auxiliary key being releasable only when the bolt of the master lock is drawn, an operating and a release key for each secondary lock, said auxiliary key being the release key for the first 70 secondary lock of the series, the operating key of each secondary lock being the release key of the next succeeding secondary lock of the series.

3. A locking system including a plurality 75 of independent lock devices, and means whereby no lock of the system can be operated to locked condition until the succeeding lock of the system has first been operated to locked condition.

4. A locking system including a recording lock device and a plurality of independent secondary locking devices, and means whereby the recording lock device can not be operated to unlocked condition until all the 85 secondary lock devices have been operated to locked condition.

5. A locking system including a recording lock device and a plurality of independent secondary lock devices, and means whereby 90 the recording lock device cannot be operated either to locked or unlocked condition until all the secondary lock devices have been operated to locked condition.

6. A locking system including a recording 95 lock device and a plurality of independent secondary lock devices, and means whereby the recording lock device cannot be operated either to locked or unlocked condition until all the secondary lock devices have been 100 operated to locked condition in sequential order.

7. A locking system including a plurality 105 of independent lock devices, and means whereby no lock of the system can be operated to locked condition until all the succeeding locks of the entire system have been operated to locked condition in sequential order.

8. A locking system consisting of a plurality 110 of independent locks each including a bolt operating and a key releasing device, and means whereby when one of the said devices is operated to released condition the other is locked against operation.

9. A locking system consisting of a plurality 115 of independent locks, each requiring a bolt operating and a key releasing key and means whereby when one of said keys is inserted and operated to locked condition the other is released, the released key of one lock being required for the operation of the next successive lock of the system.

10. A locking system consisting of a plurality 120 of independent locks each including a bolt, a bolt-operating section and a key releasing section, and a means whereby when the bolt of any lock is shot the key releasing

section thereof is rendered operable to hold the bolt in shot condition and the bolt operating section is locked against operation.

11. A locking system consisting of a plurality of independent locks each including a shouldered bolt, a key operated section for moving the bolt, a key operated release section having a cam to coöperate with the shoulder on the bolt, when the latter is shot to hold the same in shot position, the release section operating key being releasable only when the cam is in engagement with the shoulder on the bolt and the bolt operating key being releasable only when the bolt is withdrawn from shot position, the bolt operating key of one lock constituting the release section operating key of the next succeeding lock of the system.

12. A locking system consisting of a plurality of independent locks each including a key operated lock and a key operated release section, and an auxiliary locking rod, and means whereby the lock bolt cannot be shot until the auxiliary locking rod is in locking position, the bolt operating key of one lock forming the key release section operating key of the next succeeding lock of the system.

13. A locking system consisting of a plurality of independent locks each including a key operated bolt and a key operated release

section, and an auxiliary locking rod, said rod having a notch to permit the bolt to be operated only when the rod is in locking position.

14. A locking system consisting of a plurality of independent locks each including a key operated bolt, a key operated release section, and an auxiliary locking rod, said bolt having a rib and said rod having a notch coöoperating with the rib, whereby said bolt can be operated only when the bolt is in locking position.

15. A locking system consisting of a plurality of independent locks, each including a bolt, a key operated bolt actuating section and a key operated releasing section, and means whereby when either of said sections is actuated to operative position the operating key of either section is released, the bolt operating key of one lock constituting the operating key for the release section of the next lock of the system.

In testimony whereof I have signed my name to this specification, in the presence of two subscribing witnesses, on this 17th day of September A. D. 1913.

WILLIAM P. LOCKE.
